His ATTORNEY.

UNITED STATES PATENT OFFICE.

BANNER J. JOHNSON, OF KANSAS CITY, MISSOURI.

GATE.

1,364,934.

Specification of Letters Patent. Patented Jan. 11, 1921.

Application filed January 22, 1920. Serial No. 353,280.

To all whom it may concern:

Be it known that I, BANNER J. JOHNSON, a citizen of the United States, residing at Kansas City, in the county of Jackson and

5 State of Missouri, have invented a certain new and useful Improvement in Gates, of which the following is a specification.

My invention relates to improvements in gates.

10 The object of my invention is to provide a gate which is simple in construction, which is strong and durable and cheap to manufacture, which may be erected by an unskilled person, which is not liable to get out 15 of order, and which may be easily operated in all kinds of weather.

The novel features of my invention are hereinafter fully described and claimed.

In the accompanying drawing, which 20 illustrates the preferred embodiment of my invention,

Figure 1 is a side elevation of my improved gate, shown mounted in a fence.

Fig. 2 is a horizontal sectional view on the 25 line 2—2 of Fig. 1,

Fig. 3 is a cross section on the line 3—3 of Fig. 1.

Fig. 4 is a cross section on the line 4—4 of 30 Fig. 1.

Similar reference characters designate 35 similar parts in the different views.

1 designates a vertical post set in the ground and having extending through it two parallel horizontal tubes 2 and 3, disposed one above the other, and having their opposite set of ends extending through another vertical post comprising two vertical members 4 which are spaced apart from each other and which are mounted at their lower 40 ends in the ground, and have clamped between them by transverse bolts 5 two pairs of blocks 6, between which are respectively clamped the front ends of the tubes 2 and 3. A horizontal bar 7 may connect the upper ends of the two members 4 and the upper end of the post 1.

8 designates a gate provided at its front end and near its lower side with a bracket 9 in which is mounted a supporting roller 10 50 adapted for travel on any smooth surface, such as concrete 11 embedded in the ground.

The rear end of the gate 8 has attached to it near its lower side a bracket 12 in which is mounted a supporting roller 13 which 55 travels on the tube 3.

Loosely slidable respectively in the tubes

2 and 3, are two horizontal parallel guide rods 14 and 15, the front end of the rod 14 being rigidly attached by two clamping nuts 16 to the front end of the gate 8. 60

The front end of the guide rod 15 extends through a downwardly projecting arm 17 of the bracket 9, to which arm the front end of the guide rod 15 is secured by two nuts 18, which bear respectively against the 65 front and rear sides of the arm 17.

The posts 1 and 4 may be part of a fence to which are attached the fence wires 19.

In the operation of my invention, the roller 10 running on the concrete surface 11 70 and the roller 13 running on the tube 3 support the gate 8, and the rods 14 and 15 serve as guides for the front end of the gate. The bracket 9 serves the triple function of a brace for the lower front corner of the 75 gate, as a bearing for the roller 10, and as a support for the front end of the guide rod 15. The guide rods 14 and 15 running in the tubes 2 and 3 prevent the roller 13 from disengagement with the tube 3 in case the 80 latter becomes coated with ice.

I do not limit my invention to the structure shown and described, as many modifications, within the scope of the appended claims, may be made without departing 85 from the spirit of my invention.

What I claim is:—

1. In a gate, the combination with two posts, of two parallel horizontal tubes connecting and supported by said posts, and a 90 gate having two guide rods respectively loosely and slidably fitted in said tubes, and having two supporting rollers, one of which is adapted to travel on one of said tubes and the other of which is adapted to travel on a 95 suitable supporting surface on the ground.

2. In a gate, the combination with two posts, of two parallel horizontal tubes disposed one above the other and connecting and supported by said posts, and a gate having two guide rods attached to the gate near the forward end thereof and respectively loosely slidably fitted in said tubes, the gate having two supporting rollers attached respectively to the forward and rear ends of the gate, the rear roller being arranged to travel on the lower one of said tubes, and the forward roller being adapted to travel upon a suitable surface on the ground. 105

3. In a gate, the combination with two posts, of two parallel horizontal tubes disposed one above the other and extending

through and supported by said posts, and a gate having two brackets attached respectively to the front and rear ends of the gate, two rollers respectively mounted on said 5 brackets, the rear roller being arranged for travel on the lower one of said tubes and the front roller being adapted to travel on a suitable surface on the ground, and two guide rods respectively loosely and slidably 10 fitted in said two tubes, the upper rod being attached to the gate near the front end thereof, and the lower rod being attached to said front bracket.

4. In a gate, the combination with a post 15 comprising two vertical members and two sets of blocks, each set comprising two blocks bolted to and between said members, of two horizontal parallel tubes respectively clamped between the two sets of blocks, and 20 a gate slidable between said two members and having two guide rods respectively slid- able in said tubes and attached at their front ends to the front end of the gate.

5. In a gate, the combination with a post 25 comprising two upright members spaced apart from each other and two sets of blocks, each consisting of two blocks held clamped to and between said members, of two horizontal parallel tubes respectively 30 clamped between said two sets of blocks, a gate slidable between said two members and having two guide rods respectively slid- able in said tubes and attached at their front ends to the front end of the gate, the gate 35 having two supporting rollers mounted re- spectively at its front and rear ends, the rear roller being adapted for travel on one of said tubes, and the front roller being adapted for travel on any smooth support- 40 ing surface, and a post supporting the other set of ends of said tubes.

6. In a gate, the combination with two 45 posts, of a horizontal tube supported there- by, and a gate having a guide rod slid- able in said tube and attached at its front end to

the front end of the gate, and two rollers mounted respectively at the front and rear ends of the gate, one of the rollers being adapted to travel on said tube and the other roller being adapted to travel on any smooth 50 supporting surface.

7. In a gate, the combination with two 55 posts, of a horizontal tube supported there- by, and a gate having a guide rod slidable in said tube, the gate having attached to its front lower corner an angular bracket embrac- 60 ing said corner, the front end of the guide rod being attached to said bracket, and a supporting roller mounted in said bracket.

8. In a gate, the combination with two 65 posts, of a horizontal tube supported there- by, and a gate having attached to its front and rear ends respectively two brackets, two rollers respectively mounted in said brack- 70 ets, one roller being adapted for travel on said tube and the other roller being adapted to travel on any smooth supporting surface, and a guide rod slidable in said tube and having its front end attached to said front bracket.

9. In a gate, the combination with two 75 posts, of a horizontal tube supported there- by, and a gate having its front lower corner embrac- 80 ed by a bracket having a depending arm, a supporting roller mounted in said bracket, and a guide rod slidable in said tube and having its front end attached to said depending arm.

10. In a gate, the combination with two 85 posts, of a horizontal tube supported there- by, a horizontal supporting member mount- ed on said posts, and a gate having a guide rod slidable in said tube and provided with two carrying rollers, one adapted to travel 90 on a suitable support and the other adapted for travel on said supporting member.

In testimony whereof I have signed my name to this specification.

BANNER J. JOHNSON.
